UNITED STATES PATENT OFFICE.

HOWARD PHILLIPS, OF DETROIT, MICHIGAN.

ELEVATOR-GATE SHOE.

1,299,220.

Specification of Letters Patent.

Patented Apr. 1, 1919.

Application filed November 4, 1918. Serial No. 261,009.

To all whom it may concern:

Be it known that I, HOWARD PHILLIPS, a citizen of the United States, residing at Detroit, in the county of Wayne and State of Michigan, have invented new and useful Improvements in Elevator-Gate Shoes, of which the following is a specification.

This invention has reference to a novel means of operating the shoes on elevators 10 used for operating the gates.

The principal object of the invention is to provide automatic means for moving the shoe into operative position to open the gates when the car is stopped.

15 Another object of the invention is to provide means for preventing damage to the parts if the gate operating means should fail to act for any reason.

The invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several views, and in which:—

30 Figure 1 is a diagrammatic view showing my invention in use.

Fig. 2 is an enlarged view, partly in section of the invention.

35 Fig. 3 is a front view of the shoe.

Fig. 4 is a detail view of a modification.

My invention is adapted for use on elevators where the gates are operated by a separate machine. A draw bar 1 runs the full 40 length of the shaft and this draw bar is vertically movable by the before mentioned machine. Slots 2 are cut in the draw bar at each floor and a shoe 3, carried by the car is used to press a pawl 4 into the slot to raise 45 the gate. These elements are well known in the art and will not be described in detail.

50 My invention relates to means for automatically moving the shoe into position to strike the pawls when the car stops at any particular floor, the said shoe being normally out of contact with the pawls.

In carrying out my invention I pivot the shoe 3 to the arms 5 and these arms are hinged to a part of the car, as at 6. I prefer to provide one of the arms with a knuckle 55 joint, as at 7. A solenoid 8 is suitably con-

nected with the car between the arms, and the coil of this solenoid is electrically connected with the starting and stopping mechanism of the car. The sliding core 9 of the 60 solenoid is connected with one of the arms 5 by means of the link 10. The other arm, the one provided with the knuckle joint, is connected with the end of the solenoid by a coil spring 11. It will be seen that when the 65 solenoid is deenergized the spring will force the shoe outwardly away from the car, when said shoe will be in a position to engage the pawls to force them into engagement with the gates. As soon as the car is started the 70 solenoid will be energized so that the core will be drawn inwardly to move the arms against the tension of the spring and thus move the shoe into inoperative position.

By my invention the car will run smoothly 75 without noise and the shoe and pawls are not subject to wear. The knuckle joint will allow the shoe to collapse if the same should strike any obstruction, and thus not bend the arm. This construction of arm will al- 80 low the device to be used without the sole- noid.

When desired, or necessary, I provide means for limiting the outward movement of the solid arm 5. I do this by means of a 85 bolt 15, engaging a slot 16 in said arm and having a screw threaded end engaging a bracket 17 secured to a part of the elevator. This arrangement of parts is shown in Fig. 4.

90 It is thought from the foregoing description that the advantages and novel features of my invention will be readily apparent.

I desire it to be understood that I may make changes in the construction and in the 95 combination and arrangement of the several parts, provided that such changes fall within the scope of the appended claims.

I claim as my invention:—

1. A device of the class described, comprising a shoe, a pair of arms hinged to the car and pivotally connected with the shoe, one of said arms being formed of two parts, a knuckle joint connecting the two parts together, a solenoid carried by the car and having its coil electrically connected with the starting means of the car, a core for the solenoid, a link connecting the same with the solid arm and a coil spring connecting one of the parts of the sectional arm with a part 105 of the solenoid.

2. A device of the class described, com-

prising a shoe, a pair of arms hinged to the car and pivotally connected with the shoe, one of said arms being formed of two parts, a knuckle joint connecting the two parts together, a solenoid carried by the car and having its coil electrically connected with the starting means of the car, a core for the

solenoid, a link connecting the same with the solid arm, a coil spring connecting one of the parts of the sectional arm with a part of the solenoid, and adjustable means for limiting the outward movement of the solid arm. 10

In testimony whereof I affix my signature.

HOWARD PHILLIPS.
